UNITED STATES PATENT OFFICE.

GEORGE W. DUVALL AND NORMAN H. BEEBE, OF DAVENPORT, IOWA, ASSIGNEES TO
LEE BROOM & DUSTER COMPANY, OF DAVENPORT, IOWA.

BROOM-BUNCHING MACHINE.

1,179,167.

Specification of Letters Patent.

Patented Apr. 11, 1916.

Application filed August 17, 1914. Serial No. 857,157.

To all whom it may concern:

Be it known that we, GEORGE W. DUVALL and NORMAN H. BEEBE, citizens of the United States, residing at Davenport, in the 5 county of Scott and State of Iowa, have invented certain new and useful Improvements in Broom-Bunching Machines, of which the following is a specification.

This invention relates to an improvement 10 in broom bunching machines, and the object is to provide means for connecting a plurality of brooms together by threading a cord or tape through the brooms.

The invention consists of still other novel 15 features of construction and combinations of parts which will be hereinafter described and pointed out in the claims.

In the accompanying drawings: Figure 1 is a view in side elevation; Fig. 2 is a top plan view with the covers and shields removed showing the internal moving parts; Fig. 3 is a perspective view of the sliding head with a portion of the head broken away to show the manner 20 of actuating the head; Fig. 4 is a perspective view of one of the eccentric roller pins; Fig. 5 is a view in elevation and partly in section of the needle-adjusting screw; Fig. 6 is a view in elevation of the 25 needle rollers showing the needle in section supported by the roller; Fig. 7 is a detail view of a spring for holding the head in its forward position; and Fig. 8 is a detail sectional view showing the slot through which 30 the needles pass in the body.

A represents the body or frame of the machine supported upon a pedestal 1. Slidably mounted upon the frame and within the sides thereof is a head 2.

The head 2 is provided with a rack bar 3, which extends longitudinally thereof, and which meshes with a pinion 4 mounted on the shaft 5, which shaft is journaled in the body A. A crank handle 6 is connected to 40 the shaft for rotating the same. Connected to the head are needles 7, 7. These needles are fastened to the head by means of screws 8, 8, which pass therethrough and through the sides of the head, and are capable of being 45 adjusted for moving the needles transversely of the body. The needles pass through elongated slots 9 in the forward end of the body A, and in some instances, it is necessary 50 to bring the needles closer together

than in other instances, this depending entirely upon the size of the broom.

An opening 10 is formed in each side of the body A, through which a screw driver can be inserted for engaging the screws 8 when the head is moved to the forward end 60 of the machine for the purpose of adjusting the position of the needles 7.

Pins 11 are mounted in the sides of the body adjacent to the end thereof, and are held in position by thumb screws 12. These 65 pins are provided with studs 13, which are eccentrically mounted thereon. Some antifriction means, such for instance, as a grooved roller 14 is mounted on each side of the studs, and is held thereon by means of 70 cotter pins 15. These antifriction means or rollers 14 are located in the rear of the slots 9, so as to receive or separate the needles 7. The pins 11 are intended to be adjusted the same, for instance, as the screws 8, when it 75 is necessary to move the needles 7 transversely of the machine. The screws 8 are held in their adjusted positions by means of thumb screws 16, so that it is necessary to release the screws 12 and 16 from the rollers 80 or pins 11 and the screws 8 before any adjustment can be made of the needles 7.

A spring 17 is connected to the base of the body A, and is provided with a stop 18 thereon, which is adapted to engage the rear 85 end of the head 2 for holding the head at the forward end of the machine during the placing of the brooms upon the needles. The link 19 is connected to the spring and is connected to a lever 20 which is fulcrumed 90 practically midway of its length to the post 1, so that upon the actuation of either end of the lever 20, the spring 17 will be drawn downward for releasing the head 2, so that the head can travel rearwardly upon the rotation of the shaft 5. Stops 21 are formed at the forward edge of the head, and on the under side thereof for engaging the bosses 22 on the body A for limiting the rearward movement of the head. An extension or 95 shield 23 is connected to the rear end of the body A, and is adapted to cover the top of the machine for limiting the movement of, and covering, the head 2, as it is moved rearwardly to its limit of movement. The upper 100 part of the body is covered by means of covers or lids 24 and 25, so that nothing will fall into the machine, and interfere with the 105

operation of the head. In the operation of the machine, the head 2 is moved forward to the position as shown in Fig. 2, and the brooms are placed thereon. The operator 5 will first force a broom onto both needles, and then will force a broom on each needle, and so on, until the needles have a sufficient number of brooms thereon to form a bundle. The needles are provided at their outer ends 10 with eyes 26, through which a cord or tape 27 is inserted, as indicated in Fig. 2. After the cord has been inserted through the eyes of the needles, the spring 17 is released from engagement with the head 2, 15 and the head is caused to move rearwardly by rotating the shaft 5. This rearward movement of the head 2 causes the forward end of the machine to act as a stripper for forcing the brooms from the needle. As the 20 needles are drawn through the brooms, the thread or cord will be drawn through the brooms, and upon the removal of the needles, the ends of the strings will be tied together for tying the several brooms together. 25 With a machine of this character, wherein horizontal needles are provided, the brooms, after they have been removed from the needles, or the needles have been withdrawn from the brooms, and the thread or cord has 30 been drawn through the brooms, will have a tendency to lean against the end of the machine until the operator of the machine can tie the ends of the cord together for fastening the brooms together. 35 Another object of this invention is in the provision of closed eye needles, so that there is no danger of the eyes catching and damaging the twine with which the broom is sewed. Furthermore, by using movable needles, the operator is always close to the 40 brooms, as they are released from the needles, and if necessary can catch them if there should be any danger of the brooms falling to the floor and becoming disengaged.

It is also very difficult to force the brooms onto a large needle, and large needles will either displace or break the twine with which the broom is sewed, and to overcome these objections, we use small needles, which serve the purpose, and as they are not needed or used as guides for the stripper, the life of the needles is not impaired, as would be true if it was necessary to move a stripper lengthwise of the needles, rather than moving the needles in removing the brooms therefrom.

We claim:

1. In a broom bunching machine, the combination with a frame, a movable head, needles connected to the head, and means adjustably supported on the frame for governing the elevation of the needles.

2. In a broom bunching machine, the combination with a frame, a head and means for moving the head back and forth, of needles carried by the head and extending through the end of the frame, means for adjusting the needles laterally, and adjustable anti-friction means carried by the frame for supporting the needles as they are moved in and out.

3. In a broom bunching machine, the combination with a frame having elongated horizontally disposed slots in the forward end, of a head fitted to the frame, means for moving the head in and out, needles secured to the head extending through the slots, separate and independent means for adjusting the needles, both horizontally and vertically, one means connected with the frame and the other with the head.

In testimony whereof we affix our signatures in the presence of two witnesses.

GEORGE W. DUVALL.
NORMAN H. BEEBE.
